WHEEL PULLER

George E. Blackwood, Jr., Detroit, Mich., assignor
to The Imperial Brass Manufacturing Company, Chicago, Ill., a corporation of Illinois

Application December 14, 1937, Serial No. 179,698

7 Claims. (Cl. 29—85)

My invention relates to tools and particularly to pullers for dismounting wheels from their shafts.

Among the objects of my invention is the provision of a new and improved wheel puller for pulling wheels of a variety of styles from the ends of shafts upon which they are mounted.

Another object is the provision of a new and improved wheel puller which is adapted to be clamped to the wheel prior to the pulling operation and which continues to remain in clamped position.

Another object is the provision of a new and improved wheel puller which is adjustable in a manner permitting it to be clamped to wheels having spokes spaced at either 120° or 180° intervals or fractions thereof in order that a true axial pull may be exerted upon the wheel to remove it from the shaft.

Still another object is to provide a puller for wheels having oppositely disposed spokes, which is provided with a means for mounting the puller upon the wheel in a non-tiltable position, regardless of the directional disposition of the shaft, so that the puller remains in true alignment throughout the entire pulling operation.

A further object is to provide a wheel puller equipped with hook members of a new and improved design adapted to be drawn into engagement with the spokes of a wheel, and so formed that the area of contact between the members is large regardless of what the particular cross sectional configuration of the spokes may be, in order to minimize undue strain, said hooks being formed likewise in such a shape and cross section that they may be attached to spokes separated from adjacent spokes by a minimum amount of space.

A still further object is the provision of a puller for wheels of different styles in which the spokes are variously shaped and arranged, said puller being adapted, when engaging the spokes, to contact a considerable portion of the surface and to be clamped thereto by means operable at all times independently of the force applied to remove the wheel from the shaft.

Other objects and advantages will appear as the description proceeds, taken in connection with the accompanying drawings which form a part of this application.

In the drawings:

Fig. 1 is a longitudinal elevation of my device attached to a wheel and shown partly in section.

Fig. 2 is a longitudinal elevation at right angles to Fig. 1.

Fig. 3 is an end view of the device positioned on a wheel.

Figs. 4 and 5 are side and end views, respectively, of one of the hook members.

Fig. 6 is a small scale end view of a wheel showing the hook members, partly in section, attached at three balanced points of contact.

Fig. 7 is a view taken on the line 7—7 of Fig. 6 looking in the direction of the arrows.

Fig. 8 is a perspective view of the device with three hook members in place.

While I have shown in the drawings and will herein describe in detail the preferred embodiment of my invention, it is to be understood that I do not thereby intend to limit the invention to the specific form disclosed, but aim to cover all modifications and alternative constructions falling within the spirit and scope of the invention as expressed in the appended claims.

In the embodiment chosen to illustrate the principles of my invention, the device is shown attached to pulley wheels of a type customarily used on refrigeration compressors. In one instance the puller is shown attached to a wheel having conventional spokes and in another instance to a wheel having spokes in the shape of fan blades. Due to the compactness with which refrigeration compressor equipment is designed, the pulleys and the shafts upon which they are mounted are frequently located in more or less inconvenient or inaccessible places, making the pulling job a difficult one.

An additional difficulty in providing a pulley or wheel puller generally adapted to all of the circumstances which might arise is the tendency for different manufacturers to make wheels in different patterns and styles as, for example, some with spokes at 180° intervals or fractions thereof, and others with spokes at 120° intervals or fractions thereof. Furthermore, and particularly when the spokes take the shape of fan blades, they are quite apt to be positioned close together leaving only a narrow wedge shaped space between contiguous blades so narrow at times that the adjacent edges overlie each other near the hub.

In supplying a puller suitable for operation under any and all such circumstances, resort has been had to a novel construction and arrangement of hook members for grasping the spokes near the hub and in addition a clamping arrangement cooperable with the hook members for securing the puller to the wheel in such a manner that during all stages of removal the pull will be in a true axial direction.

The puller has a body formed with a radially extending flange or lifting portion to which the plurality of hook members are pivotally secured for grasping the spokes of a wheel. Forming part 5 of the body is a longitudinally extending, axial portion to which is attached a threaded sleeve extendable into contact with the hub of the wheel. A thrust screw is located at the center of the device designed to be forced against the shaft upon 10 which the wheel is mounted to remove it therefrom.

Figs. 1, 2 and 3 show the invention attached to a spoked pulley wheel 1 mounted upon a shaft 2 by means of a hub 4 from which spokes 3 radiate 15 outwardly at right angles from each other and terminate in a rim 5. The spokes here shown have the more or less conventional oval cross section and emanate from a hub having two flat surfaces, one at the outer face and one at the inner 20 face of the wheel.

The wheel or pulley puller consists basically of the body previously referred to, indicated generally by the numeral 10 in the drawings, having two principal parts, namely, the radially extending lifting portion embodied in a flange 11, and the longitudinally extending, axial portion designated by the numeral 12. The flange 11 is constructed substantially circular in cross section and has a group of three flat areas 13 circumferentially disposed about the perimeter with the centers spaced equidistant one from the other at angles of 120°, and an additional flat 14 spaced an angular distance of 180° from one of the first identified areas.

In the operative set-up shown in Figs. 1, 2 and 3, a pair of hook members 15 are located at the flat areas 13 and 14, respectively, where they are swivelly secured by pivot supports comprising the studs 16 and 17 threaded into apertures 13' and 40 14' extending inwardly from the respective flat areas. By being pivotally mounted the hook members are permitted to swing freely through any arc. The same hook members also are interchangeable from one flat area to another so that 45 a three-way or two-way grip may be had as desired, and are furthermore reversible in order that the hook members may be so mounted as to be applied to the wheel from whichever direction offers the most convenient access, or so as to permit the 50 best possible contact between the hook members and the spokes. The axes upon which the hook members swing intersect at a common center point and radiate outwardly equidistant one from the other in a direction perpendicular to the direction of a central axis through the body.

Each hook member is built with a grasping portion at the free end thereof comprising a positive hook or finger 18 of ample length provided with an angular recess 19 formed by the surfaces 20 and 20' for surrounding and grasping a spoke, there being provided also a lip 21 at the tip of the hook high enough to keep the spoke from slipping out of the recess. The hook has ample width, as best seen in Fig. 5, so that a large contact area with the spoke is assured. A shank or connecting portion 22 is proportionately smaller and somewhat trapezoidal in cross section and connects the hook 18 with a supporting end 23 provided with a hole 24 for attaching it to the 55 body. The shank furthermore takes the form of a curve whose convex side 25 distends in the same direction generally as the end of the hook supporting the lip 21. A design of this sort will always assure a considerable length of the shank 70 lying along the line of force as the hook member

is swung back and forth to engage spokes of different cross sectional area.

Forming part of the clamping means is a sleeve member 30 threaded on the inside to correspond with outer threads provided on the axial portion 5 12. The threaded engagement will be observed to permit extending the sleeve adjustably outwardly from or inwardly toward the body merely by grasping and rotating it manually. At the lower end of the sleeve a circular rim 31 is provided, larger in diameter than the largest shaft which would be anticipated, so that the rim of the sleeve when extended will comfortably surround the shaft and seat upon the hub of the wheel. The sleeve has a length such that, when extended, 15 the rim 31 is almost flush with the hook 18, while leaving a substantial section encircling the axial portion 12 of the body to maintain a rigid support. The sleeve is likewise short enough so that it can be withdrawn to a position against the 20 flange 11 leaving ample space between the rim and the hooks to permit them to be swung freely into position around the spokes of a wheel.

A thrust member embodied in a screw 35 lies on the central axis and is threaded through the center of the body at the upper portion, as viewed in Figs. 1 and 2, and extends freely through a cylindrical space in the axial portion of the body and the sleeve. The screw may be provided with a point 36 at one end for centering it in the shaft 30 of the wheel to be pulled and a square head 37 at the other end to be grasped by a wrench.

Fig. 6 shows another style of pulley wheel 1', adapted to be pulled by the applicant's device, provided with spokes 3' constructed in the shape 35 of fan blades. The fan blade spokes number six in all, are centered about the hub 4', and terminate in a rim 5'. A shaft 2' supports the wheel. In this instance the spokes are spaced at intervals of 60° one from another so that in order to pull 40 a wheel of this design three of the hook members 15 are required. The hook members are in this instance swivelly mounted at the three flats 13 of the flange 11, no hook member being attached at the flat 14. By the use of three hook 45 members every alternate spoke can be grasped so that the pull is evenly distributed on all sides.

Moreover, when the spokes have a somewhat curved cross section, such as the fan blade shown in Fig. 7, the angular recess 19 of the hook provides a secure grip and the ample length of the 50 grasping portion permits the entire blade 3' to be received therein.

When the spokes, or fan blades such as 3', are positioned close together so that the wedge 55 shaped space between them is extremely narrow adjacent the points of engagement with the hooks, the detachable feature of the hook members becomes of considerable importance. When it is not possible to swing the hooks into place 60 they can be removed, inserted under the spokes at the wider part of the wedge shaped space, and then shifted radially inwardly to be reattached to the body. The wide hook portions at the end will then extend diagonally outwardly 65 under the spokes and the somewhat narrower shanks will be sufficiently small to permit them to extend endwise between the close-set spokes.

In operation, the hook members, two or three in number depending upon the number of spokes 70 in the wheel, are swung into place around the spokes adjacent the hub of the wheel. Next the sleeve 30 is extended from the body into contact with the hub and there tightened in place by hand so that the puller is clamped in erected 75

position upon the wheel, as shown for example in Fig. 3. The wheel puller will then be rigidly attached in balanced position upon the wheel preparatory to the final pulling operation. With the puller thus in proper alignment, the mechanic by use of a wrench rotates the screw 35 until the point 36 centers in the shaft and pushes against it, thereby extending the body 10 and the flange 11, comprising the lifting portion of the body, endwise from the shaft to extract the wheel therefrom.

It is to be noted that the pull is perfectly balanced on all sides of the wheel and that the device is prohibited by action of the sleeve 39 from tilting during any part of the operation. Furthermore, even when the wheel is comparatively loose upon the shaft, there is no premature dislodgement of the puller, a common fault in devices of this sort heretofore used. In pullers of ordinary design, a shift in the position with respect to the wheel is apt to cause binding by tilting the wheel slightly upon the shaft before the final withdrawal. A frequent result in such an event is a scoring or denting 25 of the shaft aperture in the hub, or of the shaft itself, if indeed the puller is not dislodged from the wheel entirely. The permanent grasp of the applicant's puller upon the wheel prevents accidents and permits the mechanic to comfortably lift the wheel from the shaft after it has been completely and entirely freed.

I claim as my invention:

1. A puller for a wheel comprising a body, a plurality of members swingably supported on the body having wheel grasping portions of fixed and equal length for engaging parts of the wheel on one lateral face thereof at points of contact equidistant one from the other, a threaded axial portion on the body and a sleeve 35 threaded upon said portion forming a single central extension means adapted to be extended into contact with the hub of the wheel on a face opposite from and centrally with respect to the points of contact of the swingably supported 40 means for erecting the puller upon the wheel, and means threadably engaging said body and operable independently of said sleeve extendable through said axial portion and said sleeve into contact with the shaft upon which said 45 wheel is mounted and adapted to be forced against the shaft in order to remove the wheel and attached puller therefrom.

2. A wheel puller for removing from their respective shafts wheels having spokes at spaced 50 intervals of 120° and 180° and fractions thereof respectively comprising a body having supports circumferentially disposed at 120° intervals about a central axis and another support spaced at 180° from one of the said first named supports, a plurality of removable hook members adapted 55 to be pivotally mounted in balanced order on said supports upon axes having fixed positions intersecting at said central axis for grasping the spokes of a wheel to be pulled, means for clamping said hook members to the spokes, and a thrust member extending through said body adapted to be forced into engagement with the shaft of said wheel to remove the wheel and attached puller from the shaft.

70 3. A wheel puller for spoked wheels comprising a body having a longitudinally extending axial portion and a radially extending lifting portion, a pair of hook members each swivelly secured to the lifting portion upon a common axis positioned 75 perpendicularly to the axial portion, said hook

members being provided with fingers for grasping the spokes of the wheel, a sleeve member threadably engaged upon the axial portion of the body extendable centrally in an axial direction so that when the fingers are engaged around the spokes 5 on one face of the wheel the sleeve can be forced centrally with respect to the points of engagement against the hub on a face opposite so as to erect the body by a single adjustment non-tiltably in position upon the wheel regardless of the axial 10 disposition of the shaft upon which the wheel is mounted, and a thrust member on the body positioned independently of the sleeve member adapted to be forced into contact with the shaft in the same direction as said sleeve member to withdraw 15 the wheel therefrom.

4. A wheel puller for removing from their respective shafts wheels having spokes of arbitrary cross section positioned so that there is present only narrow wedge shaped spaces therebetween 20 comprising a body having a plurality of rigid supports arranged circumferentially about a central axis, a plurality of detachable hook members pivotally mounted on said supports on axes extending perpendicular to the direction of the central 25 axis, each of said hook members including a wide flat grasping portion adapted to contact the spokes over a proportionately large area and a connecting portion of comparatively small cross sectional area for permitting detached hook mem- 30 bers after the insertion in the wider parts of said wedge shaped spaces to be shifted radially toward the hub of the wheel there to be attached to said body, and means on the body forcibly extendable into contact with the shaft to remove the wheel 35 therefrom.

5. A puller for wheels having spokes in the shape of fan blades positioned with portions of the alternate edges overlying each other comprising a body provided with a lifting portion 40 having circumferentially disposed supporting elements integral therewith, a plurality of removable hook members having portions adapted to be pivotally mounted in balanced order on said supporting elements on radially disposed axes, each 45 of said hook members including a wide hook-shaped grasping portion adapted to engage a single blade over a proportionately large area and having a length in excess of the width of the blades adjacent the point of engagement so as to 50 protrude obliquely outward between the overlying edges and a lip for engaging the opposite side of the blade to secure the hook thereto, said arrangement being adapted to permit the hook members after insertion individually between ad- 55 jacent blades near the outer circumference of the wheel to be shifted radially inwardly toward the hub of the wheel there to be attached to said body, and means extendable through the body into contact with the shaft for forcibly removing 60 the wheel therefrom.

6. A wheel puller for removing from their respective shafts wheels having spokes spaced at intervals of 120° and 180° and fractions thereof respectively comprising a body having supports 65 circumferentially disposed at 120° intervals about a central axis and another support spaced at 180° from one of said first named supports, a plurality of removable hook members adapted to be pivotally suspended in any balanced order on said 70 supports upon axes intersecting at said central axis, said hook members being identical in form, reversible, and having each a flat hooked grasping portion adapted to engage one side of the spokes over a proportionately large area and 75

- 5 having a length in excess of the spoke width so as to protrude obliquely outwardly between the spokes to permit the hook members to be shifted radially into positions close to the hub, an axial portion on said body lying between the suspended hook members and having threadably mounted thereon a sleeve extendable into clamping engagement with the hub to anchor the hook members to said wheel, and a thrust member threadable axially through the body and the axial portion thereof adapted to be forced into engagement with the shaft of said wheel to remove the wheel therefrom.
- 10 7. A puller for a wheel comprising a body, a plurality of members swingably supported on the body having wheel grasping portions of fixed and
- 15

equal length for engaging parts of the wheel on one lateral face thereof at points of contact equidistant one from the other, a threaded axial portion on the body and a sleeve threaded upon said portion forming a single central extension means adapted to be extended into contact with the hub of the wheel on a face opposite from and centrally with respect to the points of contact of the swingably supported means for erecting the puller upon the wheel and means for engaging said body and operable independently of said sleeve extendable into contact with the shaft upon which said wheel is mounted and adapted to be forced against the shaft in order to remove the wheel and attached puller therefrom.
